(57) **CLAIM**

The ornamental design for a strand chuck O-ring tool, as shown and described.

DESCRIPTION

FIG. 1 is a top perspective view of a strand chuck O-ring tool showing my new design.

FIG. 2 is a bottom perspective view thereof.

FIG. 3 is a front elevational view thereof, with the left, right and rear elevational views being the same as FIG. 3.

FIG. 4 is a top plan view thereof.

FIG. 5 is a bottom plan view thereof.

FIG. 6 is a front elevational view thereof with a number of O-rings shown in dashed lines on the strand chuck O-ring tool.

FIG. 7 is a top plan view corresponding to FIG. 6; and,

FIG. 8 is a cross-sectional view thereof taken along line 8-8 in FIG. 4.

The broken lines in FIGS. 6 and 7 are directed to environment and form no part of the claim.
